UNITED STATES PATENT OFFICE

2,521,583

SLIDING AND SWINGING WINDOW

Joseph Kemp, Baltimore, Md.

Application October 1, 1945, Serial No. 619,462

1 Claim. (Cl. 20—44)

1

This invention relates to improvements in windows and more particularly to a combined sliding and swinging window construction.

An object of this invention is to provide a window construction wherein the two sashes may be normally locked for vertical sliding movement but either one or both of the sashes may be swung inwardly by removal of one of the stops so that the selected or both of the sashes may be cleaned on the outside or the window opened fully.

Another object of this invention is to provide an improved means for slidably mounting the sashes in the window frame so that these sashes may be freely moved either vertically or may be swung about their vertical axes.

With the above objects in view, and others which may hereinafter more fully appear, I have invented the device shown in the accompanying drawings wherein are shown embodiments of the invention, but it is to be understood that changes, variations or modifications may be resorted to which fall within the scope of the invention, as claimed.

In the drawings:

Figure 1 is a detail side elevation of a window construction embodying this invention.

Figure 2 is a sectional view taken on the line 2—2 of Figure 1.

Figure 3 is a sectional view taken on the line 3—3 of Figure 2.

Figure 4 is a sectional view taken on the line 4—4 of Figure 1.

Figure 5 is a sectional view taken on the line 5—5 of either Figures 2 or 3.

Figure 6 is a fragmentary side elevation of one of the stop securing means.

Figure 7 is a sectional view taken on the line 7—7 of Figure 6.

Referring to the drawings the numeral 10 designates generally a window frame construction which includes vertical side members 11 and 12, an upper horizontal member 13 and sill 14. Upper and lower sashes 15 and 16 are slidably disposed in the frame 10, and are adapted to also have horizontal swinging movement as will be hereinafter described.

A pair of outer stops 17 and 18 are secured to the side members 11 and 12, and are engaged by the upper side of the upper sash 15. A pair of inner removable stops 19 and 20 are secured to the side members 11 and 12, and are engaged by the inner side of the lower sash 16. A pair of parting stops 21 and 22 are secured to the inner sides of the side members 11 and 12 between two sashes 15 and 16.

The stop member 20, which is the inner stop, is removable from the side member 12, being removably secured by means of a pair of U-shaped channel members 23 which are disposed adjacent the upper and lower ends of the stop 20.

2

The channel member 23 is secured to the side member 12 by means of one or more screws 24, and preferably the channel member 23 is countersunk into the inner face of the side member 12, being seated in a recess 25 formed in the side member 12. The channel member 23 is formed with a pair of opposed flanges 26 so as to slidably hold a nut 27 in the channel member. A bolt 28 is adapted to threadably engage the nut 27 and preferably the bolt 28 extends through a plate 29 secured to the inner side of the stop 20 by fastening members 30. The channel member 23 is formed with a right angular stop 31 at its inner end so as to limit the inward movement of the nut 27. The parting stop 22 is also removably secured to the side member 12 by means of channel member 32 which is similar in every detail to the channel member 23, and a bolt 33 extends through the stop 22 there being two of these bolts adjacent each end of the stop 22 which is threaded into the nut 34 engaging in the channel member or keeper 32.

A pair of vertically disposed guide rods 35 and 36 are disposed in inwardly spaced relation with respect to the side member 11, the rods being of light construction and secured in threaded sockets 37 and 38 respectively at their upper ends.

The lower ends of the rods 35 and 36 are disposed in rings 39 and 40 respectively, which are secured to the lower end of the side member 11 on the inner face thereof. The rod 35 is braced between the ends thereof by means of a pair of looped straps 41 engaging about the rod 35 and each strap 41 is formed with an eye or loop 42 which is split, and has extending outwardly therefrom a pair of arms 43 which terminate at their outer ends in right angular lugs or slide members 44.

A channelled guide member 45 is mounted in a vertically disposed recess or slot 46 formed in the inner side of the side member 11, and the channel member 45 is formed with confronting flanges 47 which form a guideway for slidably holding the lugs or slide members 44. The outer sash 15 has secured thereto upper and lower slide members 48 and 49 and an intermediate slide member 50. The slide members 48, 49 and 50 are of light construction and include a plate 51 secured by fastening members 52 to the inner side of the sash 15, and also include an eye or loop 53 which loosely engages about the rod 35.

The bracing members 41 are disposed on the upper sides of the lower and intermediate slide members 49 and 50 and preferably the bracing members 41 may be fairly tight with respect to the channel member 45. In this manner the slide members 41 will frictionally hold the upper sash in a selected lowered position.

60 The inner rod 36 is braced between the ends

thereof by means of a pair of bracing members 54 and 55 which are similar in every detail to the bracing members 41, and slidably engage in a flanged channel member 56 which is countersunk in a recess 57 formed in the side member 11.

The outer sash 15 is formed with a vertical rabbet 58 in the side member 59 thereof for loosely receiving the guide rod 35, and the bracing members 41 and the side member 60 of the inner sash 16 is also formed with a rabbet 61 within which the rod 36 loosely engages and the bracing members 54 and 55 also loosely engage.

The inner sash 16 has secured thereto a plurality of spaced apart plates 62, 63 and 64. The plates 62, 63 and 64 are upper, lower and intermediate plates and each plate has formed integral therewith an eye or slide member 65, 66 and 67 which slidably engage the rod 36. In order to provide a means whereby the lower sash 16 may be held in a partially or completely upraised position, I have provided a bolt 68 which is threaded through a sleeve 69 extending transversely through the side member 60. The bolt 68 is adapted to bind against the rod 36, and the inner end of the bolt 68 is provided with wings 70 by means of which this bolt may be readily tightened or loosened.

The upper sash 15 is held in the desired vertical position by means of a bolt 71 which is similar in every detail to the bolt 68.

In order to provide for retaining the two sashes in their normal positions I have provided pairs of spring-pressed bolts 72 and 73 which are carried by the side members 74 and 75 of the upper and lower sashes. The bolts 72 and 73 are adapted to slidably engage in U-shaped channel members 76 and 77 which are countersunk in the inner side of the side member 12. In this manner when the inner stop 20 is removed the lower sash 16 may still be moved vertically and is prevented from swinging inwardly until the pair of bolts 73 are pulled inwardly. The upper sash 15 is also slidably held adjacent the outer stop 18 by means of the pair of spring-pressed bolts 72. The upper sash 15 cannot be swung inwardly until both the inner or intermediate or parting stops 20 and 22 respectively are removed.

In the use of this window construction the parting stops 20 and 22 are normally disposed, as shown in Figure 4, and in the event the locking bolts 68 and 71 are loose with respect to the rods 36 and 35 respectively, the sashes 15 and 16 may be freely moved vertically.

In the event it is desired to lock either one or both of the sashes in either closed or partly open position the bolts 68 and 71 are turned inwardly to bind against the guide rods 36 and 35 respectively.

The sashes 15 and 16 may be swung inwardly by loosening the bolts 28 on the inner stop 20, and removing this stop, this permitting the lower sash 16 to be swung inwardly irrespective of whether the bolts 68 is in locked position or is loose. It will be understood that the threaded engagement of the rod 35 in the socket 38 is such as to permit partial turning of the rod 36 in the event this rod is locked by the bolt 68.

When the sash 16 has been swung inwardly the parting stop 22 may be removed and the upper sash may be swung inwardly by pulling the bolt 72 inwardly to released position with respect to the channel 76.

It will be apparent from the foregoing that the sashes may be moved up and down in the normal

manner, and may be locked in any desired position, and that if desired these sashes may be swung inwardly for cleaning the outer sides of the window panes or for other purposes. It is

not necessary during the summer weather to replace the inner and parting stops 20 and 22 respectively as the two sashes are slidably held in their normal positions by means of the spring-pressed bolts 72 and 73. The parting stops form weather strips which may be used in cold weather during which time the sashes will not be swung inwardly.

I claim:

A combined sliding and swinging window structure comprising a window frame having vertical side members, and horizontal top and bottom members, inner, outer, and parting stops on said side members, means removably securing said inner and parting stops to said side members, an outer sash slidably disposed between said outer and parting stops, an inner sash slidably disposed between said inner and parting stops, a vertically disposed guide rod disposed between said outer and parting stops spaced therefrom and from the side member on one side of said frame, a second vertical guide rod between said inner and parting stops on one side of said frame, said rods being of a length slightly less than the distance between said top and bottom frame members, a plurality of slide members carried by each of said sashes rotatably engaging the adjacent one of said rods, threaded sockets carried by said frame adjacent the top thereof, the top ends of said rods threadably engaging said sockets for rotary movement therein, eye members secured to said one side member adjacent the lower end thereof, locking means carried by said slides engageable with said rods for locking said sashes in selected sliding position, spring pressed bolts carried by said sashes for holding the latter against swinging movement, a first vertically extending inwardly opening channel member disposed in said one side member between said outer and parting stops, a second vertically extending inwardly opening channel member disposed in said side member between said inner and parting stops, a plurality of bracing members frictionally engaging in each of said channel members, said bracing members in said first channel member slidably and rotatably receiving said first guide rod between the slide members engaging said first rod, and said bracing members in said second channel member slidably and rotatably receiving said second guide rod between the slide members engaging said second rod whereby said bracing members will stiffen said guide rods intermediate the length thereof and frictionally resist sliding motion of said inner and outer sashes relative to said frame side members.

JOSEPH KEMP.
